UNITED STATES PATENT OFFICE.

J. F. WINSLOW AND J. SNYDER, OF TROY, NEW YORK.

MACHINERY FOR MAKING RAILROAD-CHAIRS.

Specification of Letters Patent No. 9,510, dated December 28, 1852.

To all whom it may concern:

Be it known that we, JOHN F. WINSLOW and JOHN SNYDER, of Troy, Rensselaer county, New York, have invented a certain new and useful Machine for Making Wrought-Iron Chairs for Fastening the Rails of Railroads, of which the following is a full, clear, and exact description, reference being had to the accompanying drawings, making part of this specification, in which—

Figure 1 is a perspective view, Fig. 2 a longitudinal vertical section, and Fig. 3 a cross vertical section taken at the line X—X' of Fig. 2; Fig. 4 a face view of the movable cutter; Fig. 5 a perspective view of the plate of iron from which a chair is to be made; Fig. 6 a perspective representation of the chair completed, and Fig. 7 a horizontal section of the mold on which the lips of the chair are formed.

The same letters indicate like parts in all the figures.

In our newly invented machine we make said railroad chair from square plates of wrought iron, and make two cuts in the two opposite sides and form the two lips which secure the web of the rail by bending over on each side the piece of the plate between the two cuts, the projecting pieces on each side of the lips being afterward punched to receive the spikes by which the chair is secured to the timbers.

The plate of iron is introduced by hand with the two opposite edges resting on two cutters stationary at that time, and then a vertically sliding cutter, having four cutting edges, is brought down, which makes the four cuts leaving the two parts which are to form the lips resting on the two then stationary cutters. The vertically sliding cutter is formed with flat faces that rest on the four parts of the plate on each side of the parts which are to form the lips, and this cutter carries what we denominate the mold or former, the under face of which is flat and flush with the under face of the cutter, so that as the cutter is forced down with the mold or former, the plate is carried down onto the bed of the machine, bending up the lips over the inner edges of the stationary cutters which are beveled to facilitate this operation. This brings the lips in a vertical direction, and they are then thickened or upset to give additional strength by forcing down two dies onto the

edges, and then as soon as this is effected, the two parts which constitute the stationary cutters in the first part of the operation are forced downward toward each other to complete the bending of the lips over the edges of the mold or former.

In the accompanying drawings *a* represents a frame adapted to the desired purpose but which may be modified at pleasure and *b* the bed on which the chair *c* is held during the operation of bending over the lips *d*, *d*. There are two horizontal slides *e*, *e*, placed one on each side of the bed and working in ways *f*, *f*. They are worked in and out by two levers *g*, *g*, the upper arms of which are alternately acted upon on opposite sides by opposite cams *h*, *i*, on the cam shaft *j*, which receives motion from the driving shaft *k*, by a pinion *l*, and cog wheel *m*. When these slides are forced inward toward each other, the space between their inner ends is about equal to the breadth of the chair between the lips and their width is equal or nearly so to the length of the lips of the chair. Their upper faces are beveled off at *n*, *n*, and their under faces from their inner ends cut out in a curve as at *o*, *o*, to give the required curve to the lips of the chair when bending them over. The angles formed by their sides and upper faces are made sharp to form what we denominate the stationary cutters or shears, for they are stationary at the time of cutting.

At the commencement of the operation the slides *e*, *e*, are drawn back, a plate of iron of the form represented in Fig. 5 is laid on as shown by dotted lines in Fig. 3, and the movable cutter *p*, is forced down to effect the cutting and partial bending of the lips. This movable cutter is a block of metal on the lower end of a vertical bar *q*, which slides vertically in appropriate ways in the frame, its tread being properly rounded or provided with a friction roller to receive the action of a cam *r* on the cam shaft to force down the cutter, and the bar is afterward drawn up by being provided with pins *s*, *s*, one on each side which are acted upon by counter or cam grooves *t*, *t*, made in the inner face of two wheels *u*, *u*, on the cam shaft and placed on each side of the cam *r*. This movable cutter is formed with a flat face cut out at *v* to fit over the stationary cutters before described, the edges being made sharp to act as shears. At right angles to this it is cut out to

receive the mold or former *w*, which slides therein freely but accurately, the under face of the said mold or former being flush with the bottom face of the cutter.

5 From the foregoing it will be obvious that when the cutter is forced down, its under face will come onto the upper face of the plate of iron and its four faces *x*, *x*, *x*, *x*, together with the face of the mold or former 10 will cover the entire face of the plate of iron except so much of it as rests on the two stationary cutters; and hence as it descends it will make four cuts *y*, *y*, *y*, *y*, (Fig. 6) at the same time bending up the two lips 15 *d*, *d*, (Fig. 6) bringing them in a vertical position, and finally grip the plate onto the bed. So soon as the plate has been carried down on the bed and gripped as above described, two dies *z*, *z*, are forced down to 20 upset and give additional thickness to the lips. These dies are fitted to slide in ways made in the sides of the movable cutter block *g* and extend up by the sides of the cutter bar and are forced down at the appropriate time 25 by two cams *a*', *a*' on the wheels *u*, *u*, and so soon as the cams have passed the dies are thrown up out of the way by helical 30 springs *b*', *b*'. The cams *h* then force the two sides *e*, *e*, inward to bend the lips *d*, *d* 35 of the chair over the edges *c*', *c*', of the mold or former to complete the chair. This being done the other two cams *i*, *i*, draw back the slides to relieve the chair. But before the chair can be entirely relieved and 40 discharged, the mold or former must be withdrawn which is effected in the following manner: The mold or former, as stated before, slides horizontally in the cutter block. One end has the lips *c*', *c*', cut out as shown in Fig. 7, and the other is connected by a joint link *d*' with a sliding bar *e*' which works in appropriate ways *f*'. One end of the bar *e*' is bored out to receive

a helical spring *g*' which is confined by a plunger *h*', so that the tension of this spring 45 tends constantly to keep the mold in place, and when the chair is to be discharged, the mold is drawn back by a cam *i*' on a shaft *j*', receiving motion from the main cam shaft *j*, by the cog wheels *m* and *k*' which strikes a 50 projection *l*' on the bar. So soon as the cam has passed, the mold is forced back by the spring preparatory to another operation.

We have above described the mode of construction and arrangement which we have 55 essayed with success, but we do not wish to be understood as confining ourselves thereto as the construction and arrangement may be greatly varied without changing the principle of our invention.

What we claim as our invention and desire to secure by Letters Patent is—

1. The movable cutter for making the cuts in the edges of the plate, substantially as described, in combination with the slides, 65 which answer the purpose of stationary cutters and rests to effect the partial bending of the lips and which afterward complete the bending of the lips, substantially as described. 70

2. We also claim in combination with the cutter as described the making of the mold or former to slide therein for discharging the chair after it has been formed as described. 75

3. And finally we claim the dies for upsetting and giving additional thickness to the lips, as described, in combination with the bending slides and cutter, substantially as described.

JOHN F. WINSLOW.

JOHN SNYDER.
